UNITED STATES PATENT OFFICE.

WILHELM MAYBACH, OF CANNSTATT, GERMANY.

HEAT-EXCHANGER.

1,120,956.

Specification of Letters Patent. Patented Dec. 15, 1914.

Application filed September 9, 1913. Serial No. 788,913.

To all whom it may concern:

Be it known that I, WILHELM MAYBACH, a subject of the King of Wurttemberg, residing at 9 Freiligrathstrasse, Cannstatt, 5 in the Kingdom of Wurttemberg, German Empire, have invented certain new and useful Improvements in Heat-Exchangers, of which the following is a specification.

This invention relates to heat exchangers 10 for heat radiators, cooling apparatus and the like and has for its object to increase the efficiency of such apparatus.

Hitherto, the air has usually been caused 15 to traverse the heat-radiating surfaces in a direction parallel thereto. This has the drawback that the heat is absorbed only by the air nearest the heat-radiating surfaces. Moreover, the air being superheated is thus rendered dangerous to the health, when employed for heating buildings, while furthermore it gradually absorbs less heat as it rises until it at last ceases to absorb any heat. The heating surface is thus very inefficiently utilized.

25 According to the present invention, alternate adjacent air inlet and outlet conduits are provided, which are open at their longer sides, these conduits being arranged short distances apart and directed at their open 30 sides toward the heat-radiating surfaces so that the air entering the inlet conduits under either natural or artificial draft traverses the heating surfaces over the whole length of the conduits, passing transversely around their inner edges, and is thus 35 heated and passes away through the outlet conduits, so that the whole of the air supplied is uniformly heated, without being superheated to a degree dangerous to health, 40 while, moreover, the greatest possible adsorption of heat is attained. The conduits and heating surfaces are preferably inclosed in a draft-inducing casing. Furthermore, the entry and exit openings of the conduits 45 are inclined, so that the cross-sectional area of the air passage through the draft-inducing casing is in no way or inappreciably diminished by the conduits thereby also resulting in a saving in material for the conduits, which may also be retained by arranging the conduits adjacent to each other with a common partition.

In order that the invention may be more clearly understood, reference is made to the 50 accompanying drawings which show vari-

ous embodiments of my invention by way of example.

Figure 1 illustrates a heat radiator constructed according to the present invention and is a vertical sectional view on the line A—B of Fig. 3. Fig. 2 is a side view of the radiator shown in Fig. 1 but with the outer casing in section. Fig. 3 is a transverse sectional view on the line C—D of Fig. 1. Figs. 4 and 5 are fragmentary views corresponding to Fig. 3 showing two modifications thereof. Fig. 6 is a vertical sectional view illustrating a water cooler constructed according to the present invention.

On the drawings, Figs. 1 to 3, *a* designates the heat radiator, heated internally by a hot fluid such as hot water, hot air or steam, *b* the air inlet conduits, and *c* the air outlet conduits. The conduits *b* and *c* are formed from sheet-metal plates bent to 70 form parallel sides *d'* turned inwardly at their edges to form flanges *d* and connected together by an inclined side *d''*, the channel thus formed being triangular in side view, as seen in Fig. 1, and constituting the air 75 outlet conduit *c*. This outlet conduit *c* is open at its upper end *e*, the open end being preferably inclined as seen in Fig. 1. The space between the parallel side plates *d'* of adjacent channels constitutes the air 80 inlet conduit *b* and is closed at its upper end by means of an inclined plate *b'*. The radiator *a* is provided in the usual manner with vertical ribs *f*, one of which is preferably adapted to project into each of the conduits *b*. The whole is inclosed in a casing *g* 85 having openings *g'* below for the entry of air and continued upwardly above the radiator *a* to increase the natural draft. The apex *x* (Fig. 1) of each channel coincides with 90 the sides of the casing *g*, so that the air entering the latter is compelled to enter the conduits *b*. To permit the free passage of the air through the casing *g*, the total area 95 of the air inlet openings of the conduits *b* as well as the total area of the outlet openings *e* and also the total free passage between the flanges *d* and the radiator, must each be at least approximately as large as 100 the cross-sectional area of the casing minus 105 the cross-sectional area of the radiator *a*. This is effected, as clearly seen in Fig. 1, by making the side plates *d''* and air outlet openings *e* inclined. Instead, however, of 110 making the air inlet opening long and outlet

opening short, as in Fig. 1, the size of the openings may be reversed or the apex α of the channels may be arranged at any desired point and if desired may be arranged midway between the top and bottom of the radiator a , so that in this case the air inlet and outlet openings will be of equal length.

If desired, the casing g below the apex α may be wholly dispensed with, so that the air enters the air inlet conduits b directly while the side plates d^2 of the air outlet conduits c may be of other suitable shape and serve as a casing.

The cold air entering the lower part of the casing g rises therein in the direction of the arrows indicated in Fig. 1, entering the air inlet conduits b and striking the hot surfaces of the radiator a where it is deflected around the flanges d , as indicated by the arrow in Fig. 3, thereby traversing close to the heating surfaces for a short distance and thereupon in its then heated condition escaping through the outlet conduits c . The exchange of heat thus takes place as the air passes from the inlet conduits b to the outlet conduits c uniformly over the whole heating surface, while the vertical ribs f increase the heat radiating surface exposed to the air.

In the modification illustrated in Fig. 4 the vertical ribs are alternately of increased width, as indicated at f' , so as to divide the air outlet conduits c into two separate compartments. As in Fig. 5, however, the vertical ribs may be made integral with the channel plates, the vertical rib i being bent to form an inclined side i' corresponding to the side d^2 in Fig. 1 and with a side plate i^2 flanged at its inner end at i^3 to correspond to the side plates d' and flange d in Figs. 1 to 3, the space between the rib i and plate i^2 constituting the air outlet conduit c , while the space between the vertical rib i and the side plate i^2 of the next adjacent channel constitutes the air inlet conduit b .

In Fig. 6 h designates the cooling lamellar plates of a water cooler between which are arranged air inlet conduits b and outlet conduits c , two such conduits being arranged between each pair of cooling plates h through which the cooling air may pass either under natural or under artificial draft. The conduits may also be adapted to irregular or uneven heating surfaces or to radiators of circular or oval cross-section by suitable modification thereof.

I claim:

1. A heat exchanger comprising a heat-radiating element, a plurality of alternately arranged air inlet and outlet conduits arranged at a short distance from and open toward said element, said inlet conduits being closed at their upper ends and said outlet conduits being closed below so that the air is heated in passing from said inlet conduits to said outlet conduits and passes from one conduit to the other over the whole length thereof, and a series of vertical ribs on said element.

one conduit to the other over the whole length thereof.

2. A heat exchanger, comprising a heat-radiating element, a plurality of alternately arranged air inlet and outlet conduits arranged at a short distance from and open toward said element, said inlet conduits each having an air inlet opening inclined relatively to said element and said outlet conduits each having an outlet opening inclined relatively to said element.

3. A heat exchanger comprising a heat-radiating element, a plurality of channel-shaped conduits spaced apart and arranged with their open sides a short distance from said element, said conduits being only open at the side nearest said element and at their upper ends and cover plates bridging the upper part of the spaces between said conduits.

4. A heat exchanger comprising a heat-radiating element, a plurality of channel-shaped conduits spaced apart and arranged with their longitudinal edges a short distance from said element, said conduits having their parallel sides triangular so as to be open only at the side nearest said element and at their upper ends and cover plates bridging the upper part of the spaces between said conduits.

5. A heat exchanger comprising a heat-radiating element, a plurality of channel-shaped conduits spaced apart and arranged with their open sides a short distance from said element, said conduits having triangular sides, cover plates for the upper ends of the spaces between said conduits, and an inclosing casing open above and below and touching the apices of said triangular sides.

6. A heat exchanger comprising a heat-radiating element, a plurality of triangular conduits spaced apart and of channel-shaped cross-section and flanged at their edges, said flanged edges being arranged a short distance from said element, an inclined plate covering the space between adjacent conduits, and a draft-inducing casing open above and below and touching the apices of said triangular conduits.

7. A heat exchanger comprising a heat-radiating element, a plurality of alternately arranged air inlet and outlet conduits arranged at a short distance from and open toward said element, said inlet conduits being closed at their upper ends and said outlet conduits being closed below so that the air is heated in passing from said inlet conduits to said outlet conduits and passes from one conduit to the other over the whole length thereof, and a series of vertical ribs on said element.

8. A heat exchanger comprising a heat-radiating element, a plurality of alternately arranged air inlet and outlet conduits arranged at a short distance from and open

- toward said element, said inlet conduits being closed at their upper ends and said outlet conduits being closed below so that the air is heated in passing from said inlet conduits to said outlet conduits and passes from one conduit to the other over the whole length thereof, and a series of vertical ribs on said element, one projecting into each of said conduits.
- 10 9. A heat exchanger comprising a heat radiating element, a plurality of alternately arranged air inlet and outlet conduits arranged at a short distance from and open toward said element, said inlet conduits being closed at their upper ends and said outlet

conduits being closed below so that the air is heated in passing from said inlet conduits to said outlet conduits and passes from one conduit to the other over the whole length thereof, and a series of vertical ribs 20 on said element, one projecting into each of said conduits and each alternate rib being of greater width so as to divide said air outlet conduits each into two compartments.

In testimony whereof I have affixed my 25 signature in presence of two witnesses.

WILHELM MAYBACH.
